JOURNAL BOX LID

Fred A. Frederick, Lansing, Mich., assignor to
 Motor Wheel Corporation, Lansing, Mich., a
 corporation of Michigan

Application November 27, 1946, Serial No. 712,675

7 Claims. (Cl. 308—45)

1

This invention relates to railway car journal boxes, and more particularly to hinged lids therefor.

Railway car journal boxes are provided with lid assemblies which when opened permit access to the inside of the journal box and when closed serve to prevent the entrance of dirt and moisture. In a general way it can be said that there are two types of journal box in common use. In one type the journal box is packed with oil soaked waste by which the journal is lubricated. In this type of journal box a large lid hinged directly to the journal box is provided.

In the other type of journal box oil is poured into the journal box to a level above the lower part of the journal. Such journal boxes are usually closed by a cover having a relatively small access opening above the lower part of the journal through which oil can be introduced. This cover is tightly and fixedly connected to the journal box. The access opening is closed by a hinged cap.

The present invention has for its principal object the provision of a novel form of journal box lid of the latter type which is particularly simple and economical to manufacture.

Another object of the present invention is to provide a journal box lid assembly all of the principal parts of which can be pressed from sheet metal.

A still further object is to provide a journal box lid assembly of this character in which a cap for closing the access opening is mounted for limited universal movement on a pivoted lever which is held in either open or closed position by means of a spring.

These objects will more fully appear in the following specification when read in connection with the accompanying drawings, wherein:

Figure 1 is a front elevational view of a journal box and lid assembly embodying the invention; and

Figure 2 is a fragmentary cross-sectional view taken on substantially the line 2—2 of Figure 1.

In the drawings, the numeral 10 designates a journal box having a relatively large substantially rectangular access opening therein. On the opposite upright sides of the journal box are four sets of spaced apart ears 11. Preferably the ears 11 are cast integral with the journal box.

The journal box lid assembly which closes the access opening in the journal box comprises in general a cover 12, a yoke 13, a lever 14 pivotally connected to the yoke, and a cap 15. A coiled

2

spring assembly 16 holds the lever 14 in either opened or closed position, as will more fully appear presently.

The cover 12 is a pressed sheet metal member 5 of generally rectangular cross-section somewhat larger than the wall of the journal box 10 defining the access opening. The cover is provided with an inturned peripheral flange 17. Adjacent the lower portion of the cover is a relatively small 10 circular access opening which is defined by a peripheral flange 18. The flange 18 is formed by piercing the metal of the cover and drawing the metal outwardly, as indicated in cross-section in Figure 2. Just above the flange 18 a depression 19 to receive the spring assembly 16 is provided. The cover is also furnished with ribs 20 which stiffen the relatively thin metal of the cover 12.

At points about the perimeter of the cover 12 20 which correspond with the pairs of ears 11, four lugs 21 are provided. The lugs 21 are apertured to receive bolts 22. By means of the bolts 22 and nuts 23 associated therewith the cover can be securely attached to the journal box 10. The 25 bolts 22 pass through the notches between the pairs of ears 11, as indicated in the drawings. A gasket 39 is interposed between the journal box 10 and cover 12 to prevent loss of lubricant from the journal box.

The yoke 13 is a pressed metal member of 30 generally downwardly presenting U-shaped configuration, as indicated best in Figure 1. The side of the yoke 13 adjacent the cover is provided with a flat laterally extending flange 24 35 which is securely attached to the cover by means of rivets 25. The legs of the yoke 13 at the side remote from the cover have apertures to receive a pivot pin 26 for a purpose which will presently appear.

The lever 14 is also pressed from sheet metal. 40 It is of generally U-shaped cross-section with the base of the U located toward the cover 12. The sides of the lever have apertures therethrough which receive the pivot pin 26 so that the lever may pivot on the pin.

The end of the lever 14 adjacent the pin 26 45 is provided with a cam surface 27 of the cross-sectional configuration shown in Figure 2. As will be evident in that figure, the cam surface is generally V-shaped. The purpose of this cam surface will appear presently.

Intermediate the ends of the lever 14, and in a position located centrally of the access opening in the cover 12 when the lever 14 is swung to the position shown in full lines in Figure 2, is

a spherical protuberance 30. The protuberance extends toward the cover 12. An aperture is formed in the center of the protuberance 30.

The cap 15 is a circular sheet metal member provided with a peripheral flange 28 which surrounds the flange 18 on the cover. In the center of the cap is a depression 29 of spherical configuration which receives the protuberance 30 on the lever 14. The cap is apertured centrally of the depression 29 to receive a bolt 31. The bolt 31 fits relatively loosely in the aperture in the lever and relatively snugly in the aperture in the cap 15.

A thin disk 32 of relatively resilient metal surrounds the bolt 31 and is clamped between a nut 33 on the bolt and the cap 15. The disk 32 serves the dual purpose of holding a gasket 34 against the inside of the cap 15 and cooperating with the bolt 31 and nut 33 to resiliently press the cap 15 against the lever 14.

By means of the connection between the lever 14 and the cap 15 a limited amount of universal movement between the cap and lever is permitted. The resilient disk 32 holds the two parts in snug frictional engagement, thus preventing excessive relative movement due to the jarring incident to travel, and thereby reducing wear of these parts.

The spring assembly 16 consists of two cup-shaped sheet metal stampings 35 and 36 and a coiled spring 37. The stamping 35 is located in the depression 19 and riveted to the cover by a rivet 38. The stamping 36 telescopes within the stamping 35 and the two parts together house the spring 37. The latter is a compression spring which tends to urge the stamping 36 out of the stamping 35 and against the upper cam shaped end of the lever 14.

The operation of the journal box lid is for the most part self-evident. When the parts are in the position shown in full lines in the drawings the spring 37 urges the stamping 36 against the cam surface on the lever 14 in such a manner as to force the lever and its attached cap 15 to closed position. In this position the gasket 34 engages the axially outer edge of the flange 18 and the cap 15 and gasket 34 tightly close the access opening in the cover. The cap can move a limited amount relative to the lever 14 to compensate for irregularities in the flange 18, as well as for wear in the pin 26 and lever 14.

When it is desired to lift the cap 15 from the flange 18, the lower end of the lever 14 is grasped and swung in a clockwise direction, as viewed in Figure 2, to the dotted line position in that figure. During this movement the cam surface first compresses the coiled spring 37 to a limited extent and then when the topmost portion of the cam surface reaches a vertical position the spring 37 urges the stamping 36 against that surface with sufficient force to hold the lever and its associated cap in its raised position. It is closed by pushing downwardly upon the lever 14 and the spring 37 holds it tightly in closed position.

Due to the particular construction of the various parts, all of them can be fashioned as sheet metal stampings. This is a marked improvement from the standpoint of economy over castings which have been utilized heretofore. The invention is simple and extremely rugged.

The scope of the invention is indicated in the appended claims.

I claim:

1. A journal box lid assembly comprising a cover adapted to be fixedly connected to a journal

box housing, said cover having an access opening therein, a lever pivotally connected intermediate its ends on said cover, said lever having a cam surface at one end thereof, a cap for said access opening connected to said lever between the other end of the latter and the pivotal axis thereof for limited rocking movement relative to said lever, and spring means mounted on said cover and positioned between said lever and said cover, said spring means engaging said cam surface and adapted to act against different portions of the latter to selectively hold said lever and cap in open or closed positions.

2. A journal box lid assembly as defined in claim 1 wherein said spring means includes a coiled compression spring and a housing therefor, said housing comprising a cup section fixed to said cover and a movable cup section in telescopic relation to said fixed section, said movable section engaging said cam surface.

3. A journal box lid assembly as defined in claim 1 wherein said cover is formed to provide a laterally extending flange about the periphery of said access opening, and said cap seats against said flange in the closed position of the cap.

4. A journal box lid assembly as defined in claim 1 wherein said cap is connected to said lever for limited universal movement relative to the latter.

5. A journal box lid assembly comprising a stamped metal cover adapted to be fixedly connected to a journal box housing, said cover having an access opening therein; a generally U-shaped stamped metal yoke fixedly connected to said cover at one side of said access opening, a stamped metal lever pivotally connected intermediate its ends to said yoke between the legs thereof and extending radially of said access opening, said lever having an integral cam surface at one end thereof, a stamped metal cap for said access opening connected to said lever between the other end of the latter and the pivotal axis of the lever for limited rocking movement relative to said lever, and spring means mounted on said cover and positioned between said cap and cam surface being positioned within said yoke which serves as a housing for said spring means and cam surface, said spring means engaging said cam surface and adapted to act against the latter to selectively hold said lever and cap in open or closed positions.

6. A journal box lid assembly as defined in claim 5 wherein said cap is connected to said lever for limited universal movement relative thereto.

7. A journal box lid assembly as defined in claim 5 wherein said lever extends a substantial distance beyond the side of said access opening opposite the pivotal connection of the lever and forms a handle.

FRED A. FREDERICK.
